DESIGN FOR A HANDBAG FRAME

Leo Freidman, New York, N. Y., assignor to Gold Seal Importers, Inc., New York, N. Y., a corporation of New York

Application June 21, 1940, Serial No. 93,162

Term of patent 3½ years

To all whom it may concern:

Be it known that I, Leo Freidman, a citizen of the United States and residing at New York, in the county of New York and State of New York, have invented a new, original, and ornamental Design for Handbag Frames, of which the following is a specification, reference being had to the accompanying drawing, forming part thereof, and in which:

Fig. 1 is a front elevational view of a handbag frame showing my new design;

Fig. 2 is a top plan view thereof; and

Fig. 3 is an end elevational view of one of the segments of the frame shown in Figs. 1 and 2, on a slightly enlarged scale.

The salient feature of the invention is the conformation of the frame in segmental form with identical individual segments of generally cylindrical form with tapering ends constituting equidistant restrictions along the length of the frame.

I claim:

The ornamental design for a handbag frame, substantially as shown and described.

LEO FREIDMAN.
